UNITED STATES PATENT OFFICE.

FREDERICK HUGH SMITH, OF DATCHET, ENGLAND.

MEANS FOR CONTROLLING THE SUPPLY OF VAPOR TO INTERNAL-COMBUSTION ENGINES.

No. 842,261.

Specification of Letters Patent.

Patented Jan. 29, 1907.

Application filed December 20, 1904. Serial No. 237,679.

To all whom it may concern:

Be it known that I, FREDERICK HUGH SMITH, a subject of the King of Great Britain and Ireland, residing at Home House, 5 Datchet, in the county of Buckingham, England, have invented certain new and useful Improvements in and Relating to Means for Controlling the Supply of Vapor to Internal-Combustion Engines, of which the following 10 is a specification.

My invention relates to carbureters for internal-combustion engines and to means for facilitating the control of the accuracy of the charge to the engine-cylinder and rendering 15 it reliable.

Considerable difficulties have arisen in the carbureters of internal-combustion engines in securing a reliable positive supply of vapor-laden air of substantially constant proportions 20 to the engine-cylinder, notwithstanding great variations in the speed of the engine.

My invention has for its object to secure a positive supply in a very simple and reliable manner, operated from the suction of the engine. 25

My invention consists of the features and combination and arrangements of parts hereinafter described, and particularly pointed out in the claims.

Referring now to the accompanying drawings, which illustrate my invention and form part of my specification, Figure 1 is a sectional elevation of a carbureter constructed according to my invention, the section being 30 taken on the line X X of Fig. 2. Fig. 2 is a plan of my improved carbureter. Fig. 3 is a sectional elevation of the carbureter shown in Fig. 1, the section being taken on the line Y Y of Fig. 2. Fig. 4 is a sectional 35 plan on the line Z Z, Fig. 3, showing the springs which in some cases I may use to regulate the admission of air through the auxiliary air-ports. Fig. 5 is a sectional elevation of two carbureters according to the 40 present invention, these carbureters being arranged side by side and applicable for use with double or quadruple engines. Also we may use three combined for three or six cylinders, the section being taken on the line 45 5 5 of Fig. 7. Fig. 6 is also a sectional elevation of a duplex carbureter, the section being taken on line 6 6 of Fig. 5. Fig. 7 is a sectional plan on the line 7 7 of Fig. 5.

In carrying out my invention according to

the form illustrated in Figs. 1 to 4 I provide 55 a carbureter-casing *a*, divided into two compartments by a division-plate *b*. The lower of these divisions *c* forms an oil-storage space in which spirit or oil is maintained at a nearly-constant level by means of a float *d*. Thus 60 if the oil in *c* falls below a certain level the float *d* operates the pivoted levers *e*, which in turn lift the head *f* of the valve *g*. Oil will then flow from the pipe *h* through the strainer *j* into the chamber *c*. A cap *k* may be provided 65 for obtaining access to the strainer for purposes of cleaning and the like.

The float *d* is annular, and through the central space there passes a pump-cylinder *m*, which is fixed to the division-plate *b* and is of 70 larger bore near the lower than at the upper part. Inside the part of larger bore there works a hollow plunger *n*, having a head *p*, which projects for a short distance above the division-plate *b* and carries near its upper extremity a perforated disk *o*. A block of 75 leather or other fiber *l* is interposed between the perforated disk and the pump-cylinder to act as a buffer on the descent of the disk and plunger. Ball-valves *q* and *r* are placed 80 at the lower and upper ends, respectively, of the hollow plunger. Small ports or passages *s* lead from the interior of the hollow plunger to the annular space *t*, formed in the lower part of the pump-cylinder. 85

Above the division-plate *b* the carbureting-chamber proper, *12*, is placed. This chamber is preferably jacketed, as shown, and hot exhaust-gases passing through the space *w* heat up the chamber, which heat is given off by 90 radiation to the air and fuel charge, as hereinafter explained.

In the lower part of the carbureting-chamber there is or are one or more air-ports, (shown at *x*), which is or are placed in a zone 95 below the lower surface of the perforated disk *o*. Above the disk and directly over the cap *y* there is mounted a cam *z*, supported on the spindle *2*, passing through the sides of the carbureting-chamber and having an operating-lever *3*, which may be controlled by hand, mechanically, or in any other suitable way. The cam *z* may be a circular disk mounted eccentrically on the spindle *2*. It will be seen that when the spindle *2* is turned the amount 105 of travel of the pump-plunger *n* may be varied and the quantity of oil supplied to the engine altered, as hereinafter explained.

In the upper part of the carbureting-chamber there is an auxiliary air-port 4, provided with a spring 5, Fig. 4, so that on starting the engine all the air is drawn through the port *x* and the perforated disk *o*. This spring is adjusted to open whenever the vacuum becomes so excessive as to interfere with the correct and efficient operation of the pump—as, for instance, by drawing the oil direct from the storage-chamber through the ball-valves *r* and *q* while the pump still remained at the upper end of its stroke. In some cases the auxiliary ports 4 may be controlled by means of a sleeve surrounding the outside of the carbureting-chamber and adapted to close or to throttle the supply of auxiliary air more or less, as required.

In all cases I prefer to place wire-gauze 6 over the air-inlets, so as to prevent the ingress of dust or grit along with the air. The top of the carbureter is fitted with a cap 7, having a suitable connection for jointing to the charge-supply pipe 9. To operate the oil-pump independently of the engine-suction—say at starting—a small crank 8 is supplied, which may be operated by hand in any convenient manner. A screw 10, removably attached to the bottom of the carbureter, is provided for draining the oil-chamber *c* as required.

A feature of my present invention is that the oil is sprayed on the engine side of the disk *o*, so that the carbureted air is not caused to deposit its oil by unnecessary baffling.

The operation of this carbureter is as follows: At the outstroke of the engine-piston a suction is created through the pipe 9. In consequence of this air rushes through the port *x* and impinges on the disk *o*. In this way the disk *o* is moved upward, carrying with it the pump-plunger *n*. The upward motion of the plunger *n* expels oil from the annular space *t* through the ports *s*, ball-valve *r*, into the upper part of the heated carbureting-chamber. Here the oil mixes with the air rushing in through the ports *x* and the perforations in the disk *o*. On the return stroke of the engine-piston, the disk *o* falls back in this form of gravity. Oil is thus forced through the lower ball-valve *q* and into the annular space *t*. The operation then continues as before. The travel of the pump will determine the amount of oil which is displaced or projected into the carbureting-chamber. The variation of the pump-stroke by means of the cam *z* thus forms a very easy and efficient method of regulating the richness of the charge.

In Figs. 5 and 6 a duplex arrangement of my improved carbureter is illustrated, which is essentially the same as the one hereinbefore described. A carbureter-casing *a* is divided into three compartments—viz., an oil-storage compartment *c* and two separate

carbureting-chambers 12 and 12'. In the compartment *c* a float *d*, guided centrally by a hollow stud 13, is situated, which maintains the oil in the compartment *c* at a nearly-constant level by causing the levers *e* to lift the head of the valve *q*, thereby allowing an influx of oil to take place from the pipe *h* whenever the level of the oil falls so low as to allow the float to rest on the levers. Pump-cylinders *m* and *m'* are situated on each side of the float, the plungers *n'* of which carry perforated disks *o* and *o'* on their upper ends, oil being projected into the carbureting-chambers 12 and 12' through the ball-valves *r* and *r'*, situated above the perforated disks *o* and *o'*. Air-ports *x* and *x'*, situated in the zone below the perforated disks, allow air to be drawn through the disks and mingle with the oil projected into the carbureting-chambers on the suction-stroke of the engine, the stroke of the oil-pump, and consequently the richness of the charge, being regulated by the cams *z* and *z'*, fixed to a spindle 2, operated by a lever 3. Spring-controlled auxiliary air-ports 4 and 4', situated in the upper part of the carbureting-chamber, allow an additional influx of air when the vacuum becomes so excessive as to interfere with the effective operation of the pump. The heat necessary for the vaporization of the oil is provided by

causing the hot exhaust-gases to be conducted through the jackets *w*, surrounding the carbureting-chambers. In this form the action of the pumps is rendered very reliable, because the disks *o* are subjected in both directions to the suction of the engine. Thus it is known that for purposes of balancing, say, a two-cylinder engine, the cranks are set at one hundred and eighty degrees to each other. In consequence while the one disk—say *o'*—is subjected to suction, the other disk *o* is free to fall by gravity. In this multiple form, however, the action of gravity is assisted by the engine suction on the disk *o'*. The reason of this is that a suction in the pipe 9' causes a rarefaction in the space below the disk *o'*, which space is in free communication with the space below the disk *o*, which is in consequence drawn downward.

It will be obvious also that the carbureter according to my invention may be made triple, quadruple, or in any other multiple form, as required, and I do not confine myself, therefore, to the use of the single or double form of carbureter.

Having thus described my invention, what I claim as new, and desire to secure by Letters-Patent, is—

1. A carbureter for internal-combustion engines having in combination, a spraying-chamber, a member reciprocated by the engine suction and by gravity unassisted by a spring, a spraying-pump operated by said member, substantially as described.

2. A carbureter having in combination, a

- spraying-chamber, a suction-operated member, a spraying-nozzle carried on the engine side of said member and a pump actuated by said suction-operated member.
5. A carbureter having in combination a spraying-chamber, a disk, a spraying-nozzle carried on the engine side of said disk, a pump operated directly by the disk.
10. A carbureter having in combination a spraying-chamber, a loosely-fitting disk, in said chamber a spraying-nozzle carried on the engine side of said disk a pump operated directly by the disk.
15. A carbureter having in combination, a spraying-chamber, a loosely-fitting perforated disk in said chamber, a spraying-nozzle carried on the engine side of said disk, a pump operated directly by the disk.
20. A carbureter for an internal-combustion engine having in combination on the engine induction-pipe, a spraying-chamber, a loosely-fitting disk in said chamber, said chamber having air ports or openings therein on the side of the disk remote from the engine, a centrally-disposed nozzle on the engine side of said disk and discharging oil across the path of thin streams of inflowing air, and a pump actuated by the disk.
25. A carbureter for internal-combustion engines having in combination on the engine induction-pipe, a cylindrical chamber, a jacket round said chamber, a loosely-fitting disk in said chamber, a pump-plunger operatively connected to said disk, a centrally-disposed nozzle discharging on the engine side of the disk, said chamber being provided with air ports or openings on the side of the disk remote from the engine, substantially as described.
30. A carbureter for internal-combustion engines having in combination on the engine induction-pipe, a cylindrical chamber, a jacket round said chamber, a loosely-fitting disk in said chamber, said disk having perforations therein for splitting the incoming air into fine streams, a pump-plunger operatively connected to said disk, a centrally-disposed nozzle discharging on the engine side of the disk, said chamber being provided with air ports or openings on the side of the disk remote from the engine, substantially as described.
35. A carbureter for internal-combustion engines having in combination on the engine induction-pipe, a heated spraying-chamber, a loosely-fitting disk in said chamber a pump operated by said disk, spring-controlled auxiliary air-inlet means disposed above the heated chamber.
40. A carbureter for internal-combustion engines with multiple cylinders having in combination on the engine induction-pipe, a plurality of spraying-chambers, suction-operated members, pumps operated by said members, substantially as described.
45. A carbureter for internal-combustion engines with multiple cylinders having in combination on the engine induction-pipe, a plurality of spraying-chambers, disks in said chambers, free passages, between the disk on the side remote from the engine, and pumping means operated by said disks, substantially as and for the purpose described.
50. A carbureter for internal-combustion engines with multiple cylinders having in combination on the engine induction-pipe, a plurality of spraying-chambers, disks in said chambers, nozzles carried on said disks and discharging on the engine side thereof, pumps connected directly to said disks, common air-admission ports to all said chambers, said chamber being provided with air-openings situated below said disk, substantially as described.
55. A carbureter for an internal-combustion engine comprising on the engine induction-pipe, a cylindrical chamber, a heating-jacket round said chamber, a loosely-fitting disk within said chamber, a centrally-disposed pump discharging above the disk, an eccentric cam for controlling the motions of said disk, said chamber being provided with air-openings situated below said disk, substantially as described.
60. A carbureter having in combination a spraying-chamber, a loosely-fitting disk in said chamber, a spraying-nozzle carried on the engine side of said disk, an oil-pump plunger carried by the disk, said chamber being provided with air-ports located on the side of the disk remote from the engine-cylinder, an oil-pump cylinder in which said oil-pump plunger works, substantially as described.
65. A carbureter having in combination on the engine induction-pipe, a spraying-chamber, a suction-operated member, a pump operated by said member, said pump having a cylindrical barrel, a hollow plunger of two diameters having ports therein, a foot-valve carried by the plunger at its lower end, a spraying-nozzle at the upper end on the engine side of the disk, all arranged for the purpose of spraying the oil on the upstroke of the pump, substantially as described.
70. A carbureter having in combination on the engine induction-pipe, a spraying-chamber, a suction-operated member, a fixed pump-cylinder m bored out to two diameters, a hollow plunger n , having ports s therein leading into the annular space t between the fixed cylinder and the plunger-head, a foot-valve q , a head-valve r arranged on the engine side of said suction-operated member, substantially as described.
75. A carbureter for internal-combustion engines with multiple cylinders having in combination on the engine induction-pipe, a plurality of spraying-chambers, suction-operated members, pumps operated by said members, substantially as described.
80. A carbureter for internal-combustion engines with multiple cylinders having in combination on the engine induction-pipe, a plurality of spraying-chambers, disks in said chambers, free passages, between the disk on the side remote from the engine, and pumping means operated by said disks, substantially as and for the purpose described.
85. A carbureter for internal-combustion engines with multiple cylinders having in combination on the engine induction-pipe, a plurality of spraying-chambers, disks in said chambers, nozzles carried on said disks and discharging on the engine side thereof, pumps connected directly to said disks, common air-admission ports to all said chambers, said chamber being provided with air-openings situated below said disk, substantially as described.
90. A carbureter for internal-combustion engines with multiple cylinders having in combination on the engine induction-pipe, a plurality of spraying-chambers, disks in said chambers, nozzles carried on said disks and discharging on the engine side thereof, pumps connected directly to said disks, common air-admission ports to all said chambers, said chamber being provided with air-openings situated below said disk, substantially as described.
95. A carbureter for internal-combustion engines with multiple cylinders having in combination on the engine induction-pipe, a plurality of spraying-chambers, disks in said chambers, nozzles carried on said disks and discharging on the engine side thereof, pumps connected directly to said disks, common air-admission ports to all said chambers, said chamber being provided with air-openings situated below said disk, substantially as described.
100. A carbureter for internal-combustion engines with multiple cylinders having in combination on the engine induction-pipe, a plurality of spraying-chambers, disks in said chambers, nozzles carried on said disks and discharging on the engine side thereof, pumps connected directly to said disks, common air-admission ports to all said chambers, said chamber being provided with air-openings situated below said disk, substantially as described.
105. A carbureter for internal-combustion engines with multiple cylinders having in combination on the engine induction-pipe, a plurality of spraying-chambers, disks in said chambers, nozzles carried on said disks and discharging on the engine side thereof, pumps connected directly to said disks, common air-admission ports to all said chambers, said chamber being provided with air-openings situated below said disk, substantially as described.
110. A carbureter for internal-combustion engines with multiple cylinders having in combination on the engine induction-pipe, a plurality of spraying-chambers, disks in said chambers, nozzles carried on said disks and discharging on the engine side thereof, pumps connected directly to said disks, common air-admission ports to all said chambers, said chamber being provided with air-openings situated below said disk, substantially as described.
115. A carbureter for internal-combustion engines with multiple cylinders having in combination on the engine induction-pipe, a plurality of spraying-chambers, disks in said chambers, nozzles carried on said disks and discharging on the engine side thereof, pumps connected directly to said disks, common air-admission ports to all said chambers, said chamber being provided with air-openings situated below said disk, substantially as described.
120. A carbureter for internal-combustion engines with multiple cylinders having in combination on the engine induction-pipe, a plurality of spraying-chambers, disks in said chambers, nozzles carried on said disks and discharging on the engine side thereof, pumps connected directly to said disks, common air-admission ports to all said chambers, said chamber being provided with air-openings situated below said disk, substantially as described.
125. A carbureter for internal-combustion engines with multiple cylinders having in combination on the engine induction-pipe, a plurality of spraying-chambers, disks in said chambers, nozzles carried on said disks and discharging on the engine side thereof, pumps connected directly to said disks, common air-admission ports to all said chambers, said chamber being provided with air-openings situated below said disk, substantially as described.
130. A carbureter for internal-combustion engines with multiple cylinders having in combination on the engine induction-pipe, a plurality of spraying-chambers, disks in said chambers, nozzles carried on said disks and discharging on the engine side thereof, pumps connected directly to said disks, common air-admission ports to all said chambers, said chamber being provided with air-openings situated below said disk, substantially as described.

ports being arranged on the side of the disk remote from the engine, substantially as and for the purposes hereinbefore described.

18. A carbureter for use with multiple-cylinder internal-combustion engines comprising a plurality of liquid-fuel-spraying pumps disposed in the charging-pipes to the cylinders, disks carried by the plungers of said pumps, heated chambers into which the liquid fuel is sprayed by the pumps, main and auxiliary air-openings in said heated

chamber, a liquid-fuel storage-chamber and means for maintaining a practically-constant level of liquid fuel in said chambers, substantially as described.

In witness whereof I have hereunto set my hand in presence of two witnesses

FREDERICK HUGH SMITH.
